Primary Examiner — Ian Simmons*Assistant Examiner* — Carissa C Fitts*(74) Attorney, Agent, or Firm* — Leong C. Lei(57) **CLAIM**

The ornamental design for a lantern, as shown and described.

DESCRIPTION

FIG. 1 is a front view of lantern showing my present design;

FIG. 2 is a rear view thereof;

FIG. 3 is a left view thereof;

FIG. 4 is a right side view thereof;

FIG. 5 is a top side view thereof;

FIG. 6 is a bottom view thereof;

FIG. 7 is a perspective view thereof;

FIG. 8 is a perspective view thereof, in an alternate position; and,

FIG. 9 is a perspective view thereof, in an alternate position. The broken lines shown in the drawings form no part of the claimed design.
